UNITED STATES PATENT OFFICE.

EDWARD HUTCHINSON, OF NEW YORK, N. Y.

CORNER-IRON FOR WAGON-BODIES.

SPECIFICATION forming part of Letters Patent No. 310,517, dated January 6, 1885.

Application filed August 6, 1884. (No model.)

To all whom it may concern:

Be it known that I, EDWARD HUTCHINSON, of the city, county, and State of New York, have invented a new and useful Improvement 5 in Corner-Irons for Wagon Bodies and Seats, of which the following is a full, clear, and exact description.

Reference is to be had to the accompanying drawings, forming a part of this specification, 10 in which similar letters of reference indicate corresponding parts in all the figures.

Figure 1 is a sectional side elevation of a part of a wagon-body to which my improvement has been applied. Fig. 2 is a perspective view of an upper corner of a wagon-body, 15 showing the top corner-iron. Fig. 3 is a perspective view of a lower corner of a wagon-body, showing the bottom corner-iron. Fig. 4 is a perspective view of the top corner iron, 20 showing its inner side. Fig. 5 is a perspective view of the bottom corner-iron, showing its inner side.

The object of this invention is to provide 25 corner-irons for wagon bodies and seats, so constructed that they will be lighter, stronger, and neater than the ordinary corner-irons.

The invention consists in the construction hereinafter described and claimed.

A represents a wagon-body, to the upper 30 corners of which are attached the top corner-irons, B. The top corner-irons, B, are made in the form of angular plates, and have flanges C formed along their side edges to overlap the sides of the top edge of the corners of the body 35 A, and thus hold the said corners from opening. The inner corner of the angle-iron B is curved, as shown at b, to form a strengthening-brace, as will be readily understood.

To the lower corners of the wagon-body A 40 are attached the bottom corner-irons, D, which are made in the form of triangular plates and have flanges E formed along their edges. The flanges E along the edges adjacent to the right angle are designed to overlap the outer 45 side of the side and end boards of the wagon-body A, and the flanges E opposite the right angles are designed to be let or driven into the lower side of the corner of the frame of

the wagon-body and the lower edges of the side and end boards of the said body, as indicated in Figs. 1 and 3. With this construction the corner-irons will have a firmer hold upon the wagon-body, and their strength will be increased, so that they can be made lighter and neater than when made flat in the ordinary manner. The corner-irons are designed 50 to be made of Russia iron struck up into the desired form. The top corner-irons, B, are provided with holes F, to receive screws for securing them to the upper edges of the side and end boards of the wagon-body, and the bottom corner-irons, D, are provided with holes G H, 55 to receive screws for securing them respectively to the lower edges of the side and bottom boards of the wagon-body and the lower 60 side of the frame of the said body.

I have shown and described my improvement as applied to wagon-bodies, but do not limit myself to that use, as the corner-irons 65 can be applied to the corners of wagon-seats with the same advantages as to wagon-bodies.

Having thus described my invention, I claim as new and desire to secure by Letters Patent—

1. Corner angle-irons for wagon bodies and seats made, substantially as herein shown and 70 described, with flanges along their edges and with the inner corner of its angle bent to form a brace, b, whereby the angle-irons will be able to stand greater strain at the corners or angles, as set forth.

2. The combination, with the upper edges 75 of the side and end boards of a wagon body or seat, A, of the angular plate B, having flanges C along its side edges and strengthening-brace b at the inner corner of its angle, substantially as herein shown and described.

3. The combination, with the lower edges 80 of the side and end boards of a wagon body or seat and the lower side of the body-frame, of the triangular plate D, having flanges E along 85 its edges, substantially as herein shown and described.

EDWARD HUTCHINSON.
